UNITED STATES PATENT OFFICE.

HARRISON HAYES, OF PORTLAND, MAINE.

TUBE-EXPANDER.

SPECIFICATION forming part of Letters Patent No. 325,244, dated September 1, 1885.

Application filed April 10, 1885. (No model.)

To all whom it may concern:

Be it known that I, HARRISON HAYES, a citizen of the United States, residing at Portland, in the county of Cumberland and State 5 of Maine, have invented a new and useful Steam-Boiler-Tube-Fastening Tool, of which the following is a specification.

My invention relates to improvements in steam-boiler-tube-fastening tools, in which 10 three or more single rolls are used to fasten the tube in the tube-sheet of steam-boilers; and the object of my improvement is to form a shoulder each side of the tube-sheet and at the same time force the tube firmly against 15 the tube-sheet between the shoulders, so as to produce a fastening stronger and better than can be obtained by the use of a tool with single rolls. I attain this object by the use of the tool illustrated in the accompanying 20 drawings, in which—

Figure 1 is a side view of the tool; Fig. 2, an end view of the same; Fig. 3, a sectional view on the line *d f*, Fig. 1. Fig. 4 is a view of the head of the mandrel; and Fig. 5, a sectional view of the tool on the line *g h*, Fig. 2, and of a tube and tube-sheet after being fastened.

Similar letters refer to similar parts throughout the several views.

30 A represents the stock of the tool, in one end of which are three slots at equal distances from each other, and each of which contains three hardened steel rolls, *a b c*, of varying diameters and lengths, according to the size of the shoulders required and the thickness of 35 the tube-sheet. *a* and *c* are slightly larger in diameter than the roll *b*, and the length of *b* is proportioned to the thickness of the tube-sheet.

40 The three slots in which the rolls *a b c* are placed are elongated, so that the rolls have a little motion forward and back from the cen-

ter, but cannot fall from the slots laterally. They are put in the slots at the end and held in place by the ring *D*, which is fastened to 45 the stock *A* by the machine-screws *e e e*.

B is a tapering mandrel to be driven into the central hole of the stock *A*, so as to force the rolls *a b c* into position to fasten the tube. Said mandrel is provided with holes, as at *F*, 50 Fig. 4, in its largest end, in which to insert a rod for the purpose of revolving the tool and completing the fastening.

The operation of this tool is as follows: The stock *A*, Fig. 5, is placed in the end of the 55 tube *C*, so that the rolls *b b b* shall be opposite the tube-sheet *E*, the tapering mandrel is then driven into the stock *A* until the rolls *b b b* are pressed firmly against the tube-sheet *E* and the rolls *a a a c c c* have formed a shoulder 60 each side of the same, then a rod is put in the hole *F*, Fig. 4, and the whole revolved, forming a strong, even fastening, as shown. The advantages of these sets of rolls *a a a b b b c c c* over single rolls are greater strength in the tool 65 and a better fastening of the tubes—greater strength because of three short bearings on the mandrel, instead of one long one, and a better fastening because of the shoulder each side of the tube-sheet.

Having fully described my invention, what 70 I desire to claim and secure by Letters Patent is—

The combination, in a steam - boiler - tube- fastening tool, of three or more sets of rolls, *a* 75 *b c*, in a stock, *A*, with a tapering mandrel, *B*, having a hole or holes in its largest end for the purpose of inserting a rod to revolve the tool, all as shown, described, and specified.

HARRISON HAYES.
